Mary H. Wyszynski, Hamtramck, Mich.

Application September 27, 1944, Serial No. 115,476

Term of patent 14 years

(Cl. D44—29)

To all whom it may concern:

Be it known that I, Mary H. Wyszynski, a citizen of the United States, residing at Hamtramck, county of Wayne, in the State of Michigan, have invented a new, original, and ornamental Design for a Vegetable Holder, of which the following is a specification, reference being made to the accompanying drawing, forming part thereof.

Fig. 1 is a plan view of a vegetable holder embodying my design.

Fig. 2 is an end view thereof.

Fig. 3 is a side view thereof.

Fig. 4 is a perspective view thereof.

I claim:

The ornamental design for a vegetable holder, as shown.

MARY H. WYSZYNSKI.
